UNITED STATES PATENT OFFICE.

OTTO MEYER, OF TOLEDO, OHIO.

ASH SIFTER.

Application filed December 27, 1922. Serial No. 609,296.

To all whom it may concern:

Be it known that I, OTTO MEYER, a citizen of Germany, residing at Toledo, in the county of Lucas and State of Ohio, have invented certain new and useful Improvements in Ash Sifters, of which the following is a specification.

This invention relates to ash sifters and has for its object to provide a device of such 10 class in a manner as hereinafter set forth, with an ash tray or pan for positioning in a stove or furnace to collect ashes and having means for coupling it with a rotatable sifting element mounted in a closable housing, 15 whereby the sifting operation can be carried on without creating any dust and further to overcome the necessity of shoveling or handling the ashes, otherwise than that as stated, when it is desired to sift them.

20 A further object of the invention is to provide in a manner as hereinafter set forth, an ash sifter including an ash collecting tray or pan capable of being detachably connected to and further when connected forming a continuation of a sifting element and providing a tray or pan for not only collecting the ashes from the stove or furnace, but also constituting a receptacle for holding the ashes during the sifting operation, 25 as well as providing a container for the ashes after they have been sifted.

25 Further objects of the invention are to provide an ash sifter which is simple in its construction and arrangement, strong durable, compact, efficient and convenient in its use, readily assembled, and comparatively inexpensive to manufacture.

With the foregoing and other objects in view, the invention consists of the novel 40 construction, combination, and arrangement of parts, as hereinafter more specifically described and illustrated in the accompanying drawings, wherein is shown an embodiment of the invention, but it is to be understood 45 that changes, variations and modifications can be resorted to which fall within the scope of the claims hereunto appended.

50 In the drawings wherein like reference characters denote corresponding parts throughout the several views:—

Figure 1 is a longitudinal sectional view of an ash sifter in accordance with this invention.

55 Fig. 2 is a side elevation, broken away, with the enclosing housing for the sifting element open.

Fig. 3 is a horizontal sectional view of an ash shifter in accordance with this invention, further illustrating in dotted lines the top of the enclosing housing swung to open position. 60

Fig. 4 is a fragmentary view, partly in section, illustrating the ash tray or pan connected with the sifting element.

An ash sifter in accordance with this invention comprises a housing consisting of a body portion 1, which is open at its top. Supporting legs 2 depend from the body portion 1, and removably mounted within the body portion 1, is a collecting receptacle 3 for receiving the sifted material from the ashes during the sifting operation. The receptacle 3 has each end thereof provided with a hand grip or handle 4. 65

The body portion 1, as well as the receptacle 3, is constructed of sheet metal, and the upper portion of the body 1 is bent upon itself to provide an outwardly extending continuous flange 5, and also for the purpose of reinforcing the upper end of the body portion 1. 75

The housing is rectangular in contour, and not only includes the body portion 1, but also a lid or cover 6, which is hinged, as at 7, to the flange 5 arranged at the rear of the body portion 1. The lid or cover 6 is formed with a flange 8 which seats on the flange 5 and is also provided with a hand grip 9 to facilitate the opening of the lid or cover 6 when occasion requires. 85

90 Each end of the lid or cover 6, has projecting inwardly therefrom, an eye 10, to which is attached a flexible element 11, the latter being also connected as at 12 with the body portion 1, and the flexible members 11, which are in the form of chains, limit the opening movements of the lid or cover 6. 95

The ash tray or pan which is adapted to be positioned in a stove or furnace for the purpose of collecting the ashes, comprises a bottom 13, a pair of side walls 14, 15, and a pair of end walls 16, 17. The ash tray or pan is preferably stamped from a single piece of sheet metal and is of flaring contour, and each of its end walls has secured to its outer face a hand grip or handle 18. Each of the end walls of the ash tray or pan is furthermore provided with a series of openings 19. 100

105 The top of the ash tray or pan is formed with an outwardly projecting split flange 20, which merges into an upwardly extending 110

and inwardly inclined split rim 21 which is somewhat resilient. The rim 21 is employed for detachably connecting the sifting element with the ash tray or pan so that the 5 said element and pan will be coupled together during the sifting operation which is had by revolving the sifting element within the housing.

The sifting element consists of a pair of 10 end plates 22, 23, each formed with an inwardly extending flange 25. Mounted upon the flange 25 as well as overlapping the front of an end plate, is an angle-shaped member 26, and positioned against the inner face of the flange 25 is a channel-shaped member 27. The flange 25, and members 26 and 27 are fixedly secured together by a series of hold fast devices 28. Arranged between the end plates 22 and 23 and extended 20 into the channel-shaped member 27, is a farrinous element 29 and which is secured in position by the hold fast devices 28.

Each of the end plates 22, 23, has its lower end formed with an outwardly extending flange 30 and secured to each side of the element 29, at the ends thereof, and interposed between the members 27, is an angle-shaped member 31. Hold fast devices 32 are employed for securing the angle-shaped 30 member 31 in position.

The flanges 30, in connection with the angle-shaped members 31, are employed for detachably connecting the sifting element to the ash pan or tray, and the said flanges 30 and members 31 cooperate with the rim 21, in a manner as shown in Figs. 1 and 3, to detachably connect the sifting elements to the ash pan or tray.

The end plate 22, as well as the end plate 40 23, is provided with a hand grip or handle 33, and each of said end plates is furthermore provided with an opening 34, having registering therewith a bearing 35, secured to the end plate by hold fast devices 36. 45 Extended through the sifting element and also through the bearings 35, is an operating shaft 37, which is fixedly secured to said sifter element by the set screws 38, carried by the bearings 35. One end of the 50 shaft 37 is extended to provide a crank or handle 39, and the other end is extended through a slot 40 in one end of the lid or cover. The shaft 37 also extends through a slot 41 formed in the other end of the lid 55 or cover.

Connected to each of the end plates of the sifting element as at 42, is a flexible member 43, carrying a holding device 44, adapted to engage over the top of the body portion 1, 60 to arrest rotative movement of the sifting element.

It will be assumed that the ash pan or tray, has been positioned within a stove or furnace, and a body of ashes collected there- 65 in, the tray or pan is then removed, and the

sifting element coupled therewith, the sifting element is then mounted within the housing 1, at the top thereof, slots 45 being provided for the reception of the shaft 37, the sifting element and ash tray, after the 70 lid or cover has been moved to closed position, is revolved within the housing, thereby sifting the ashes, the sifted particles being collected in the receptacle 3. The sifting operation under such conditions will be carried on without creating dirt. After the 75 ashes have been sifted, the sifting element and ash tray are removed from the housing, disconnected from each other, and the contents of the ash tray or pan removed. The 80 tray is then placed in position to collect another body of ashes. The sifting element is mounted upon the body portion 1 and retained in an upright position by the holding devices 44.

When the receptacle 3 is filled from the material discharged from the sifting element and ash tray during the sifting operation, it is removed from the body portion 1 and the contents of the receptacle discharged 90 at any suitable point.

From the foregoing construction, taken in connection with the accompanying drawings, an ash sifter is set up whereby the ash sifting operation can be carried on without creating any dust, and furthermore an apparatus is set up whereby the ashes can be sifted without necessity of shoveling them into the apparatus, due to the fact that the apparatus includes an ash tray or pan which can be positioned in a stove to collect the ashes, and after which coupled to the sifting element, and although the preferred embodiment of the invention is as shown, yet it is to be understood that changes in the 100 details of the construction can be had without departing from the spirit of the invention as claimed.

What is claimed is:

1. An ash sifter comprising a sifting element including a pair of end plates, bearings projecting outwardly from said plates, a shaft extending through said bearings and elements and rotatably supported on said housing and providing means for rotating 110 said sifting element, an ash tray, a plurality of angle-shaped members projecting outwardly from the bottom of said plates, and a split laterally extending flange arranged at the top of said tray and formed with an 115 inwardly extending resilient rim frictionally engaging the said members for detachably connecting the tray with the sifting element whereby the tray will be bodily revolved with said element.

2. An ash sifter comprising a sifting element including a pair of end plates, bearings projecting outwardly from said plates, a shaft extending through said bearings and elements and rotatably supported on said 120

- housing and providing means for rotating said sifting element, an ash tray, a plurality of angle-shaped members projecting outwardly from the bottom of said plates, a 5 split laterally extending flange arranged at the top of said tray and formed with an inwardly extending resilient rim frictionally engaging the said members for detachably connecting the tray with the sifting element 10 whereby the tray will be bodily revolved with said element, and means carried by the plates and engaging with the housing to arrest rotative movement of the sifting element.
- 15 3. An ash sifter comprising a sifting element including a pair of end plates, bearings projecting outwardly from said plates, a shaft extending through said bearings and elements and rotatably supported on said 20 housing and providing means for rotating said sifting element, an ash tray, a plurality of angle-shaped members projecting outwardly from the bottom of said plates, and a split laterally extending flange arranged 25 at the top of said tray and formed with an inwardly extending resilient rim frictionally engaging the said members for detachably connecting the tray with the sifting element whereby the tray will be bodily revolved 30 with said element, said sifting element in said tray being of oval contour in cross section and one forming a continuation of the other when connected together.
4. An ash sifter comprising a sifting element including a pair of end plates, bearings projecting outwardly from said plates, a shaft extending through said bearings and elements and rotatably supported on said 35 housing and providing means for rotating
- said sifting element, an ash tray, a plurality of angle-shaped members projecting outwardly from the bottom of said plates, a split laterally extending flange arranged at the top of said tray and formed with an inwardly extending resilient rim frictionally 40 engaging the said members for detachably connecting the tray with the sifting element whereby the tray will be bodily revolved with said element, and means carried by the plates and engaging with the housing to 45 arrest rotative movement of the sifting element, said element and said tray being oval-shaped in cross section and one forming a continuation of the other when connected together. 50
5. An ash sifter comprising a sifting element including a pair of end plates, bearings projecting outwardly from said plates, a shaft extending through said bearings and elements and rotatably supported on said 55 housing and providing means for rotating said sifting element, an ash tray, a plurality of angle-shaped members projecting outwardly from the bottom of said plates, a split laterally extending flange arranged at the top of said tray and formed with an inwardly extending resilient rim frictionally 60 engaging the said members for detachably connecting the tray with the sifting element whereby the tray will be bodily revolved with said element, a handle projecting from each of said plates near the top thereof, and a handle projecting from each end of said tray and arranged below said angle-shaped 65 members. 70
- In testimony whereof I affix my signature hereto.

OTTO MEYER.
